F. M. HANDLY,
VALVE LIFTER,
APPLICATION FILED AUG. 13, 1920.

1,373,885.

Patented Apr. 5, 1921.

Inventor:

Frank M. Handly;

Adelaide Kearne.

UNITED STATES PATENT OFFICE.

FRANK M. HANDLY, OF EDINBURG, INDIANA.

VALVE-LIFTER.

1,373,885.

Specification of Letters Patent.

Patented Apr. 5, 1921.

Application filed August 13, 1920. Serial No. 403,202.

To all whom it may concern:

Be it known that I, FRANK M. HANDLY, a citizen of the United States, residing in Edinburg, in the county of Johnson, State 5 of Indiana, have invented a new and useful Valve-Lifter, of which the following is a full, clear, and comprehensive specification and exposition, the same being such as will enable others to make and use the same with 10 exactitude.

The object of my present invention, broadly speaking, is to provide a valve lifting tool which is positive in action, simple in character, easily operated and adjusted, 15 and which can be manufactured and sold at a comparatively low price.

More specifically stated my object is to provide a tool for releasing and replacing the puppet valves in explosion engines, the 20 same having means whereby the tool may be adjusted to operate with various sizes and types of motors, and having means whereby the valve may be rotated by the tool when the tool is in operation.

Other minor objects and particular advantages of the invention will suggest themselves in the course of the following specification, and that which is new will be correlated in the appended claims.

The preferred means for carrying out the objects of my invention in a practical and economical manner is shown in the accompanying drawings, in which—Figure 1 is a side elevation of my tool as it would appear 35 in actual practice releasing a valve shown in connection therewith, certain portions of the motor being shown in vertical section in order to show the interior thereof. Fig. 2 is a side elevation of my tool alone, showing 40 the jaws open or spaced apart.

Fig. 3 is a central vertical section, on an enlarged scale, showing certain portions of my tool, also showing parts of a valve and the valve mechanism. Fig. 4 shows one 45 of the pronged bits alone. Fig. 5 shows a blade bit alone, and Fig. 6 shows a plan view of the spring engaging jaw of my tool.

Similar indices denote like parts throughout the several views.

In order that the construction, the operation, and the advantages of my invention may be more fully understood and appreciated I will now take up a detailed description thereof, in which I will set forth 55 the several features as fully and as comprehensively as I may.

Referring now to the drawings in detail: Letter A denotes a portion of an explosion motor, the same having an explosion chamber B, and an intake or exhaust chamber 60 C. The chambers B and C being divided from each other by the partition D which is formed integral with the motor. Letter E denotes the top of chamber B, and F denotes the bottom of chamber C. 65

Formed through the partition D is the valve aperture G, whose upper portion is formed flaring thereby providing the valve-seat for the valve H which fits therein to close the aperture G. 70

Integral and concentric with the valve H is the valve stem I, which extends down through the center of the aperture G, and through a guide or bearing aperture therefor in the bottom F, below which the stem 75 extends.

Formed laterally through the lower portion of the stem I is an aperture in which may freely operate the lock-pin J, which extends at right-angles to the valve stem. 80 Slidably mounted on and concentric with the valve stem is the inverted cup-shaped washer K, the length of the pin J being such as to extend centrally across the interior of the washer K whereby the washer will rest 85 on the pin J and prevent the removal of said pin, but when the washer is moved upward then the pin may be easily removed endwise.

Formed through the top E is a comparatively large threaded aperture L, the same 90 ordinarily being closed by a plug screwed therein. Letter M denotes the valve spring which surrounds the stem L, and it is normally in contact with the under side of the bottom F, and with surface of the washer 95 K, to hold the valve in its seat.

My invention proper includes a pair of crossed handles 1 and 2, which are pivotally connected by the bolt 3. From near the bolt 3 said handles are turned at substantially 100 right-angles to their respective main portions thereby forming the respective shanks 4 and 5 which project oppositely to each other.

Integral with but projecting forward at 105 right-angles from the shank 4 is the arm 6, and extending downward and forward from the latter is the finger 7 which terminates in the bearing member 8 which has a vertical aperture therethrough. 110

Extending forward from the shank 5 the material is given a quarter turn or twist to

form the flat disk-like and forked plate 9, whose forward portion has a notch 10 therein, in which may enter the stem I, thereby forming the two thin points 11 and 12 on each side of the notch 10 which may be inserted between the coils of the spring M, or between said spring and the washer K.

Rotatably mounted in the bearing 8 is the shaft 13 which has a head 14 on its upper 10 end, and below the bearing 8 the shaft 13 is threaded to receive thereon the collar 15 which is rigidly secured thereto.

Numerals 16, 17, 18 and 19 denote the bits, each having a stem to fit in the lower portion 15 of the collar 15 where it may be detachably secured by means of a set-screw 20. Said bits differ from each other either in the length of their stems or in the working ends of the bits, for instance, the bits 16, 17 and 20 18 have different length stems but they each have points 21 adapted to fit in cavities therefor in the top of the valve H, as in Figs. 1 and 3. Or if the valve is provided with a channel across its top then a bit with 25 a blade 22 is provided as that shown in Fig. 5.

Numeral 23 denotes a lever or handle secured in the head 14 to afford means for turning the shaft and the bit secured therewith.

Operation: Desiring to use the tool the proper bit is first secured in the collar 15, depending on the size of the motor, after which the tool is opened, as in 2, and the bit 35 is then inserted through the aperture L, bringing the bit into connection with the valve as shown in Figs. 1 and 3.

The handles 1 and 2 should now be opened to bring the plate 9 under the lower end of 40 the spring M, or between two coils of said spring, the plate 9 being then pressed between the spring and the washer K. Now by grasping the handles 1 and 2 the operator may force said handles toward each other, 45 which manifestly will contract the spring M and raise it above the washer K thereby enabling the operator to easily lift the washer and then remove the pin J. By means of the lever 23 the operator will be 50 enabled to turn the valve and the stem whereby the pin J will be turned to the most accessible position for the operator to remove it. Also if the valve or the stem be stuck then by turning the lever 23 they may be 55 revolved and thereby loosened.

As soon as the pin J is removed then the washer K will drop off the stem thereby per-

mitting the spring M also to be removed. After the above the tool should be removed, 60 after which it is evident that the valve may be removed by lifting it upward through the aperture G, thereby accomplishing the desideratum.

From the above it is evident that the means by which one is enabled to rotate the 65 valve during the process of its removal is a decided convenience as it saves much time and enables one to work much more easily.

I desire that it be understood that various 70 changes may be made in the various details of construction without departing from the spirit of the invention and without sacrificing any of the advantages thereof which are new and useful.

Having now fully shown and described 75 my invention, what I claim and desire to secure by Letters Patent of the United States, is—

1. A valve lifting tool comprising a pair of crossed handles pivoted together, a 80 notched plate carried by one of the handles and adapted to be inserted astride a valve-stem for engagement with the valve-spring, an arm and a finger carried by the other one of said handles, a bearing carried by 85 said finger, rotatable means mounted in said bearing, means for revolving said rotatable means, and a removable bit connected to said rotatable means and adapted to engage a 90 valve for holding the valve in its seat and enabling the valve to be turned, all substantially as shown and described.

2. A valve lifting tool comprising a pair of crossed members forming handles at one 95 end, a spring engaging member located on one of the working ends and a removable bit mounted opposite to the latter on the other working end, and means whereby said bit may be rotated independently of the operation of said crossed members, all substantially 100 as shown and described.

3. A valve manipulating tool comprising in combination means for releasing the pressure of the valve spring from the valve, and means carried by the tool for rotating 105 the valve and the valve stem, substantially as set forth.

In testimony whereof I have hereunto subscribed my name to this specification in the presence of two subscribing witnesses.

FRANK M. HANDLY.
